UNITED STATES PATENT OFFICE

109,047

DESIGN FOR A VANITY MIRROR OR THE LIKE

Walter J. Bohn, Toledo, Ohio, assignor to Acme Specialty Company, Toledo, Ohio, a corporation of Ohio

Application January 27, 1938, Serial No. 74,602

Term of patent 7 years

To all whom it may concern:

Be it known that I, Walter J. Bohn, a citizen of the United States, and resident of Toledo, county of Lucas and State of Ohio, have invented a new, original, and ornamental Design for a Vanity Mirror or the like, of which the following is a specification, reference being had to the accompanying drawing, forming a part thereof.

Fig. 1 is a front elevation of a vanity mirror or the like, showing my new design; Fig. 2 is a top plan view; and Fig. 3 a side elevation thereof.

I claim:

The ornamental design for a vanity mirror or the like, substantially as shown.

WALTER J. BOHN.
